William Raphael BOISVERT, Inventor

By Attorney *J. Marion*

UNITED STATES PATENT OFFICE.

WILLIAM RAPHAEL BOISVERT, OF LEVIS, CANADA.

RULER.

SPECIFICATION forming part of Letters Patent No. 586,157, dated July 13, 1897.

Application filed January 27, 1897. Serial No. 620,848. (No model.)

To all whom it may concern:

Be it known that I, WILLIAM RAPHAEL BOISVERT, a citizen of the Dominion of Canada, residing at Levis, in the county of Levis, Province of Quebec, Canada, have invented certain new and useful Improvements in Rulers; and I do hereby declare the following to be a full, clear, and exact description of the invention, such as will enable others skilled in the art to which it appertains to make and use the same.

This invention relates to rulers; and it consists in the novel construction and combination of the parts hereinafter fully described and claimed.

In the drawings, Figure 1 is a side view of the ruler. Fig. 2 is a front view of the ruler. Fig. 3 is a longitudinal section through the ruler. Fig. 4 is a plan view of the ruler.

A is an inclosing case, and B is a marking-wheel provided with a shaft *b*, which is journaled in the case. The wheel B is provided with marking-flanges *b'*.

C is a flap connected at one end to the case by hinges *c*, and *c'* is a spring-catch secured

to the case and engaging with the other end of the flap C.

D is an inking-pad, of felt or other approved absorbent material, which is secured to the flap C and pressed thereby against the flanges *b'*.

When the wheel B is rolled over a flat surface, it marks lines *e* thereon, as shown in Fig. 4.

What I claim is—

In a ruler, the combination, with a case, and a marking-wheel journaled therein and provided with flanges; of a flap hinged at one end to the case, a spring-catch connecting the other end of the said flap to the case, and an inking-pad secured to the said flap and pressed thereby against the said flanges, substantially as set forth.

In testimony whereof I affix my signature in presence of two witnesses.

WILLIAM RAPHAEL BOISVERT.
